AMUSEMENT DEVICE

Charles E. Wilson, Bluefield, W. Va.

Application February 17, 1944, Serial No. 522,769

5 Claims. (Cl. 46—120)

This invention relates to amusement devices and has relation more particularly to a device of this kind of a grotesque type and which embodies a movable figure.

Primarily it is an object of the invention to provide a device of this kind including a figure comprising a plurality of relatively movable parts so assembled as to effect a changed relation of such parts upon dropping of the figure in suspension.

It is also an object of the invention to provide a device of this kind including a figure adapted to be releasably supported at a desired height and wherein said figure has associated therewith a suspending element which does not become effective until the release of the figure and wherein said figure comprises an assembly resulting in a simulation of a stretching of the figure when dropped and at the same time effecting an outward projection of an element normally concealed within the figure.

The invention also has for an object to provide a device of this kind which in its operation and use affords a burlesque of an execution by hanging.

The invention consists in the details of construction and in the combination and arrangements of the several parts of my improved amusement device whereby certain important advantages are attained, as will be hereinafter more fully set forth.

In order that my invention may be better understood, I will now proceed to describe the same with reference to the accompanying drawings, wherein:

Figure 1 is a view in front elevation of an amusement device constructed in accordance with an embodiment of my invention;

Figure 2 is a sectional view taken substantially on the line 2—2 of Figure 1;

Figure 3 is a sectional view taken substantially on the line 3—3 of Figure 1;

Figure 4 is a fragmentary detail sectional view taken substantially on the line 4—4 of Figure 3;

Figure 5 is a view similar to Figure 4 but showing certain of the parts in a second position;

Figure 6 is an enlarged fragmentary elevational view showing the figure as herein comprised as stretched, with a normally concealed element in projection;

Figure 7 is a sectional view taken substantially on the line 7—7 of Figure 1;

Figure 8 is a view somewhat similar to Figure 7 but showing certain of the parts in a second position;

Figure 9 is a view in blank of a part placed within the upper part or head of the figure.

As disclosed in the accompanying drawings, B denotes a base plate of desired dimensions and which is herein disclosed as formed of an elongated rectangle. Extending upward from the rear margin of this base plate B is a back plate P having produced on the outer or front face thereof a scenic view including a person in a standing position.

One end portion of the base B adjacent to its forward margin is provided with a pair of upstanding posts or columns 1 of a length to extend to a point closely adjacent to the upper margin 15 of the back plate P. The upper ends of these posts or columns 1 have interposed therebetween a cross front member 2 suitably anchored in position. Interposed between the central portion of the member 2 and the back plate P is a beam or member 3 having suitably secured to the central portion thereof an extremity of an elongated flexible member M for a purpose to be herein-after more particularly referred to.

Hingedly connected, as at 4, for up and down 25 swinging movement at a desired point above the base plate B is the rear marginal portion of a platform 5. This platform 5 substantially bridges the space between the posts or columns 1 and also substantially bridges the space between the back plate P and the plane of the posts or columns 1 when the platform 5 is in its raised position.

The forward longitudinal edge of the platform 5 midway its ends is provided with an outstanding pin 6 which, when the platform 5 is raised 35 to a position substantially parallel with the base plate B, is received within a notch or recess 7 provided in the outer or free end portion of a rigid lever 8. This lever 8 has its lower end portion pivotally connected, as at 9, to an up-standing block 10 carried by the base plate B and such lever 8 is of a length to releasably hold the platform 5 in desired raised position, as particularly illustrated in Figure 3 of the drawings.

The lever 8 is positioned directly above the opening or pocket 11 provided in the base plate B and into which extends a pin 12 carried by and depending from the lower pivoted end of the lever 8. This pin 12 is adapted to be received within a notch or recess 14 provided in the inserted end portion of an elongated plunger 15 which is slidably and rotatably engaged within an opening 16.

This opening 16 is in the end portion of the base plate B and extends from the opening or pocket 11 to the outer end of the base plate B so

that the outer extremity of the plunger 15 may be normally extended beyond the base plate B to facilitate the operation of the pin when it is desired to effect the necessary rocking movement of the lever 8 to release the platform 5.

The released position of the lever 8 is illustrated in Figure 5 of the drawings and when the lever 8 is in such position, the notch or recess 14 of the plunger 15 is downwardly disposed and the pin 12 of the lever 8 so contacts with the inserted end portion of the plunger 15 or that part within the opening or pocket 11 to hold the lever 8 against return swinging movement.

A suitable figure F is adapted to be freely placed upon the platform 5 when raised and, as illustrated in the accompanying drawings, this figure F is in grotesque simulation of a human figure including a body 17 and a head 18. The head 18 is provided with a depending elongated neck 19 herein disclosed as cylindrical in form and which tubular neck extends upwardly from below within the head and into a suitable chamber 20 in the head.

The lower or extended portion of the neck 19 extends within an elongated socket 21 in the upper portion of the body 17 of the figure F whereby the neck 19 is permitted to have longitudinal movement independently of the body 17 in order to provide the effect of stretching the head 18 from the body 17 when the figure F is dropped upon release of the platform 5, as will be herein-after more particularly set forth.

The outer portion of the socket 21 is defined by an inwardly disposed flange 22 which has close contact with the periphery of the neck 19 and the extremity of the neck 19 within the socket 21 carries an outwardly surrounding flange 23. This flange 23 contacts with the flange 22 to limit the extent of relative longitudinal movement between the neck 19 and the body 17.

The lower portion of the front face of the head 18 is provided thereacross with a transverse slot 24 having communication at all points therewith along the lower part of the chamber 20 within the head 18 and through which is adapted to be freely extended or retracted a tongue 25. The upper or inner end portion of this tongue member 25 carries an inwardly and laterally disposed elongated bar 26 which extends within the upper end portion of the neck 19 or that part within the chamber 20, the wall of the neck 19 being slotted, as at 27, to allow the entrance of the bar 26 into the neck 19.

The tongue 25 and bar 26 are formed of metal or other material having required rigidity and the extremity of the bar 26 within the neck 19 is pivotally connected to the neck 19, as at 28, whereby the bar 26 is free to have up and down swinging movement, whereby the tongue 25 is either retracted within the chamber 20 or extended therefrom.

The tongue 25 is normally maintained in its retracted position by a retractile member 29, herein disclosed as an elastic band, having one end secured, as at 30, to the bar 26 and its opposite end portion secured, as at 31, to the neck 19 at a point above the pivotal connection 28.

Anchored, as at 32, to the base wall 33 of the socket 21 is an end portion of a non-elastic flexible member 34, the opposite end portion of which has secured thereto, as at 35, an extremity of an elastic member 36. The upper or outer end portion of this member 36 is anchored from below,

as at 37, to the bar 26 at a point in relatively close proximity to its pivotal mounting 28.

The tension of the elastic member 29 is greater than the tension of the elastic member 36. The elastic member 36 is provided to allow for the continued outward movement of the neck 19 after the tongue 25 has been projected to its fullest extent and, of course, as the neck 19 returns, the tension of the elastic member 29 will effect a retraction of the tongue 25.

The flexible member M has its lower extremity engaged preferably by a slip noose 38 and this member M is of such length that as the figure F is permitted to drop, the body portion 17 will continue to fall after the further downward movement of the head 18 has been limited by the member M. This action will result in the simulation of the neck of the figure F being extended and as a result of such relative outward longitudinal movement between the neck 19 and the body 17, the bar 26 will be pulled or swung toward the body 17, resulting in an extension of the tongue 25.

The figure F, or more particularly the head 18 thereof, is preferably made of molded paper stock or the like and for which reason it is of advantage to provide means to prevent any loosened matter falling into the neck 19. In the present embodiment of the invention, this is prevented by securing to the top wall of the chamber 20 an elongated strip 39 preferably of paper and which is adhesively held in place. This strip 39 at its forward end is provided with the oppositely disposed lateral extensions 40 which partially overlie the upper portion of the slot 24 and such overlying portions of the extensions 40 and the adjacent intermediate portion of the strip 39 are herein disclosed as having produced thereon grotesque representations of teeth.

40 The lever 8 at a desired point intermediate its ends has rigidly secured thereto a laterally disposed elongated bar 41 having its outer end portion operatively engaged with an articulated arm 42 carried by an upstanding figure 43 mounted upon the base plate B. This figure 43 is in simulation of a person and when the lever 8 is swung to release the platform 5, the articulated arm 42 will also be caused to move, thus creating an effect of the platform 5 being released by the figure 43.

From the foregoing description it is thought to be obvious that an amusement device constructed in accordance with my invention is particularly well adapted for use by reason of the convenience and facility with which it may be assembled and operated.

What is claimed is:

1. An amusement device of the class described comprising a platform, means for hinging the platform at a predetermined elevation, releasable means for holding the platform raised, a figure to freely rest on the platform, and means for suspending the figure when the platform is released and drops, said figure comprising parts assembled for relative movement lengthwise of the figure, such movement being effected when the platform drops and the figure is placed in suspension.

2. An amusement device as set forth in claim 1, with a movable element carried by one of the parts of the figure and adapted for retraction and extension with respect to the said one part of the figure, means for maintaining such element retracted when the figure is supported on the

raised platform, and means for extending said element when the figure is in suspension.

3. In an amusement device including a figure, suspending means for the figure, a releasable support for the figure for holding the figure independently of the suspending means, said figure dropping upon release of the support, said figure including a body having a socket in its upper portion, a head, a neck carried by the head and extending within the socket of the body, the suspending means being operatively engaged with the head, said neck being of substantial length and slidably engaged in the socket to allow relative movement between the body and head, and means limiting outward movement of the neck in the socket and the relative movement of the head and body.

4. In an amusement device including a figure, suspending means for the figure, a releasable support for the figure for holding the figure independently of the suspending means, said figure dropping upon release of the support, said figure including a body having a socket in its upper

portion, a head, a neck carried by the head and extending within the socket of the body, the suspending means being operatively engaged with the head, said neck being of substantial length and slidably engaged in the socket to allow relative movement between the body and head, and means limiting outward movement of the neck in the socket and the relative movement of the head and body, said head having a chamber and a slot in the face thereof in communication with the chamber, a tongue mounted for movement inwardly or outwardly of the chamber and through the slot, means for normally maintaining the tongue retracted within the chamber, and means for extending the tongue upon the stated relative movement between the head and body of the figure.

5. An amusement device as set forth in claim 4, wherein the means for extending the tongue comprises an expansible member operatively connected with the tongue and with the body of the figure.

CHARLES E. WILSON.
